CLAIM

The ornamental design for a vehicle wheel, as shown and described.

DESCRIPTION

FIG. 1 is a front perspective view of the vehicle wheel;

FIG. 2 is a front view thereof;

FIG. 3 is a side view thereof;

FIG. 4 is another side view thereof;

FIG. 5 is a rear view thereof; and,

FIG. 6 is a rear perspective view thereof.

The broken lines shown in the drawings depict portions of the vehicle wheel that form no part of the claimed design.
